UNITED STATES PATENT OFFICE

2,164,105

HAIR COMB

William Parker Brown, New York, N. Y.

Application January 3, 1939, Serial No. 249,111

1 Claim. (Cl. 132—19)

The present invention relates to toilet articles or devices of a character for personal use, such as a comb, and consists in the combinations and arrangements of elements hereinafter described 5 and particularly set forth in the accompanying claim.

The invention is disclosed by way of illustration in the accompanying drawing wherein:

Figure 1 is a side elevational view of the article 10 complete;

Figure 2 a transverse sectional view taken on the line 2—2 of Figure 1, and;

Figure 3 is a like view taken on the line 3—3 of Figure 1. Figure 4 is a modified form of nail 15 cleaner.

Referring to the construction in further detail and wherein like reference characters designate identical parts in the several figures, the comb is essentially of ordinary construction and 20 comprises a back portion 4 having the usual row of teeth 5 and at one end 6 is slightly curved and otherwise constructed as shown.

The end portion 7 is of appreciable thickness and has a cut-away or sharp angular portion as 25 at 8 which forms a nail cleaning edge or point 9 as clearly illustrated in Figures 1 and 3. It will therefore be seen that with this arrangement there is provided an ordinary pocket comb with one end shortened, and shaped like the cleaning 30 end of the ordinary orangewood manicure stick, so that a person has a satisfactory nail cleaner and comb in one instrument.

A further purpose or refinement in the device 35 contemplates the inclusion of a finger nail file located on one of the side surfaces of the comb back 4 and said file may have the serrations thereof impressed in the material at the time the

article is cast or moulded, provided of course the material is of sufficient hardness. However, quite apart from this the file may be provided by having a suitable recess 11 formed to receive with a close fit the metallic piece 12 after the manner 5 shown in Figures 1 and 2.

The omission of the comb teeth 5 adjacent the nail cleaning element 8, as clearly shown in Figure 1, provides an appreciable space 10 which gives the requisite clearance or room for the 10 fingers of the hand when said end portion 7 is used as a hand gripping element, and such appropriate use will be convenient in the general manipulation of the nail cleaning element of the article as will be readily understood.

In lieu of having the nail file 12 as shown it 15 may be desirable to have some filing surface made of abrasive material which is adhered to the back of the comb 4 with some suitable cement, as will be understood.

It will be understood the invention as herein disclosed is not limited to the details of construction shown and described, since these may be varied without departing from the principles 20 of the invention as defined by the claim.

What is claimed as new is:

- An article of the character described comprising, a hair comb having a back portion and rigid members projecting laterally from the ends thereof, the comb teeth immediately adjacent one 30 of said lateral end members being removed to provide an appreciable space for the fingers thereat, said adjacent end member providing a hand gripping part, and the point of said hand gripping part being cut-away to provide further 35 finger gripping space, substantially as set forth.

WILLIAM PARKER BROWN.
